UNIVERSAL BENDING MANDREL UTILIZING CONNECTING CABLE

Francis J. Fuchs, Jr., Winston-Salem, N. C., assignor to Western Electric Company, Incorporated, New York, N. Y., a corporation of New York

Application November 17, 1954, Serial No. 469,471

3 Claims. (Cl. 153—63)

This invention relates to tube bending mandrels and more particularly to mandrels for supporting thin walled rectangular tubes during the bending of such tubes which are to be used as wave guides.

In the draw bending of wave guide tubing it has heretofore been proposed to utilize flexible mandrels whereby the inner surface of the tubing being bent is supported as uniformly as possible. These mandrels have comprised serially interconnected links which were interlinked by pin connections or ball and socket connections wherein each link was spaced from its next adjacent links by a fixed amount.

It is an object of the present invention to provide a mandrel of improved construction for use in bending rectangular wave guides.

A further object of the invention is to provide a mandrel the components of which have a limited and adjustable amount of freedom of movement longitudinally of the mandrel.

In accordance with one embodiment of the invention a plurality of mandrel elements having an outer contour conforming substantially to the inner contour of the tube to be bent and each having a semispherical projection at one side and a semispherical depression at the other side, are positioned side by side and held in engagement one with the other by the upper and lower courses of flexible cable passing through apertures adjacent the ends of the mandrel elements and extending from a rigid stem through the upper ones of said apertures, through an arcuate passage in a terminal element, thence through the lower ones of said apertures in the mandrel elements and back to the stem. Preferably the stem comprises an assemblage, for attachment to the reciprocable mandrel rod of a draw bending machine, which has a cavity in it for receiving the ends of the flexible cable together with a mechanism for adjustably interconnecting the ends of the cable whereby the length of the cable may be adjusted thereby to adjust the spacing of the mandrel elements.

In another embodiment of the invention the ends of the cable are adjustably attached directly to the stem by a plurality of set screws.

A better understanding of the invention may be had by reference to the accompanying drawings wherein:

Fig. 1 is a side elevational view of a mandrel made in accordance with the present invention, part of the stem being broken away;

Fig. 2 is a top view of the apparatus shown in Figure 1;

Fig. 3 is an enlarged fragmentary side elevational view of a portion of the rigid stem, parts being broken away to more clearly illustrate the constructional features;

Fig. 4 is a transverse sectional view taken along the line 4—4 of Fig. 3 in the direction of the arrows;

Fig. 5 is a transverse sectional view taken along the line 5—5 in Fig. 3 in the direction of the arrows;

Fig. 6 is a view in perspective of a portion of the mechanism for adjustably interconnecting the ends of the cable;

Fig. 7 is another perspective view showing another portion of said mechanism;

Fig. 8 is an enlarged fragmentary sectional view through the mandrel elements taken substantially along the line 8—8 of Fig. 2 in the direction of the arrows;

Fig. 9 is a fragmentary sectional view taken along the line 9—9 of Fig. 8 in the direction of the arrows;

Fig. 10 is a fragmentary elevational view of the free end of a stem illustrating an alternate embodiment of the invention, and

Fig. 11 is a transverse sectional view taken along the line 11—11 of Fig. 10 in the direction of the arrows.

In accordance with the preferred embodiment of the invention there is provided a tube bending mandrel having a rigid stem designated generally by the numeral 15, an articulated body portion designated generally by the numeral 16 made up of a number of serially interconnected links 17 and a terminal element designated generally by the numeral 18. The links 17, as seen most clearly in Figs. 8 and 9, have slightly rounded upper and lower ends 19 and 20 and are of a length substantially equal to the inside dimension of a section of wave guide which is to be bent using the apparatus of the present invention.

The sides 21 and 22 of the links 17 are also slightly rounded and are spaced apart a distance substantially equal to the inside dimension across a section of wave guide which is to be bent by the present apparatus. Each of the links is provided with a semispherical depression 25 and a semispherical projection 26 whereby the links

when nested as shown in Figs. 8 and 9 may have a limited amount of universal movement with respect to one another. The link 17 adjacent the stem 15 is formed in the same manner as the other links and the stem 15 is provided with a semispherical depression 27 at its free end for the reception of the semispherical projection on the adjacent link 17. Each of the links is provided with upper and lower bell-mouthed apertures 28 and 29 respectively for receiving a flexible cable 30, the lower course of the cable extending through the aligned apertures 29 and the upper course extending through the aligned apertures 28.

In addition to the links 17 having universal movement to a limited extent one with respect to the other and with respect to the stem 15, there is also a limited amount of universal movement possible between the terminal element 18 and the link 17 adjoining it. The terminal element 18 is composed of a pair of plates 33 and 34 suitably fastened together, for example by means of the rivets 35. The free ends of the plates 33 and 34 may, if desired, be beveled, whereby the assembled plates define a notch 38 which may be filled with solder in order to strengthen the link 18. The plates 33 and 34 are provided with arcuate grooves 36 and 37 which cooperate when the plates are fixed together to form an arcuate passageway for the reception of a loop of the cable 30. The sides of the terminal element 18 are rounded similarly to the links 17 and the plates 33 and 34 are tapered at their free end, as shown at 40 (Fig. 9), to facilitate the insertion of the mandrel into a wave guide to be bent. The outer edges of the plates 33 and 34 are rounded, as shown most clearly at 41 in Fig. 8, also to facilitate the insertion of the mandrel into a wave guide.

The rigid stem 15 is made from two substantially rectangular elongated bars 42 and 43 which when assembled are held together by machine screws 44. Bars 42 and 43 are provided with a number of apertures through which dowels 45 may be driven to align the assembled bars with each other. At the right end of the rigid stem, as shown in Figs. 1 and 2, suitable means comprising a pin 46 and a machine screw 47 are provided for attaching the stem to the mandrel rod, not shown, of a conventional draw bending machine. Each of the plates 42 and 43 is pro-

65

70

vided with a rectangular cavity 48, only the plate 43 and its cavity being shown in detail since the plate 42 comprises a mirror image of the plate 43. In addition to the cavity 48, each of the plates is provided with a groove 49 extending adjacent to and parallel with the bottom edge of the plate as shown in Fig. 3. This groove 49 extends from the left end of the plates and then is curved through a semicircular path as shown at 50 and thence is disposed at a slight angle to the horizontal as shown at 51 and is tapered to merge with the cavity 48. An extension of the groove 49 is resumed as shown at 52 adjacent the left end of the rigid stem 15 and this extension of the groove communicates with the cavity 48 adjacent the left end of the stem. The groove 49 and its extensions formed in each of the two plates 42 and 43 will, when the plates are attached together, form a passageway for the reception of the lower and upper courses of the flexible cable 30.

The ends of the cable 30, prior to the time when the plates 42 and 43 are assembled together, have blocks 60 and 61 attached to them by means of a plurality of set screws 62. The blocks 60 and 61 are slideable in the cavity 48 and are provided with longitudinally extending bores 63 and 64 the adjacent ends of which, when the blocks are assembled as shown in Fig. 3, are oppositely threaded as shown at 65 and 66 for the reception of oppositely threaded ends 67 and 68 of a shaft designated generally by the numeral 69. The mid portion of the shaft 69 is slightly larger than the threaded portions and is provided with teeth 70 for engagement by a suitable tool which may be inserted through apertures 71 in the plates 42 and 43 to rotate the shaft 69 thereby to move the blocks 60 and 61 toward or away from each other.

In accordance with the embodiment of the invention illustrated in Figs. 10 and 11, the articulated body portion of the mandrel is the same as in the previously described embodiment. However, the ends of the cable 30 are simply attached to a rigid stem portion designated generally by the numeral 75 by means of a plurality of set screws 76. The set screws 76 are threaded into apertures 77 in a plate 78 which is provided with a pair of grooves 79 and 80 which are aligned with grooves 81 and 82 in a cooperating plate 83. The plates 78 and 83 have their right ends equipped in the same manner as the right end of the rigid stem portion 15 in the preferred embodiment of the invention and have a semispherical depression 84 at their left end, Fig. 10.

In using the apparatus of the preferred embodiment of the invention, the spacing of the links 17 longitudinally of the mandrel may be adjusted by rotating the shaft 69 which will either shorten or lengthen the cable 30 and, consequently, will adjust the pressure between the depressions 25 and 27 and projections 26 on the various links 17 whereby when it is desired to extend or shorten the articulated portion of the mandrel slightly the cable may be lengthened by rotating the shaft 69 in one direction and may be shortened by rotating the shaft 69 in the opposite direction. The adjustment of the length of the cable embodiment illustrated in Figs. 10 and 11 may be effected by loosening either the upper or lower set screws 76 and resetting them in the desired position.

Although specific embodiments of the invention have been described herein it will be understood that modifications thereof may be made without departing from the invention.

What is claimed is:

1. A tube bending mandrel comprising a rigid stem, a plurality of body links the outer contour of which conforms substantially to the interior contour of a tube to be bent, abutting surfaces of said links and said stem being formed to permit movement of each link with respect to its adjoining links and of the inner end link with respect

to the stem, and means for attaching the links one to the other and to the stem comprising a flexible element threaded through said links and having its ends adjustably attached to said stem, said stem comprising a pair of elongated bars, each of said bars having a rectangular cavity in it, means for securing said bars together in face-to-face relation with said cavities facing each other to form a block receiving cavity, a pair of blocks slidably positioned in said block receiving cavity, means for moving said blocks toward or away from each other and means for attaching the ends of said flexible element individually to said blocks.

2. A tube bending mandrel comprising a rigid stem, a plurality of body links the outer contour of which conforms substantially to the interior contour of a tube to be bent, abutting surfaces of said links and said stem being formed to permit limited universal movement of each link with respect to its adjoining links and of the inner end link with respect to the stem, and means for attaching the links one to the other and to the stem comprising a flexible cable threaded through said links, said stem comprising a pair of elongated bars, each of said bars having a rectangular cavity in it, means for securing said bars together in face-to-face relation with said cavities facing each other to form a block receiving cavity, and a pair of blocks slideable in said block receiving cavity and provided with right and left hand threaded bores, a shaft having teeth at its mid portion and oppositely threaded ends threaded into said bores, cooperating grooves in the abutting faces of said bars forming a U-shaped guide passage for said cable, and means for fixing the ends of said cable in opposite ends of said blocks.

3. A tube bending mandrel comprising a rigid stem, a plurality of body links the outer contour of which conforms substantially to the interior contour of a tube to be bent, abutting surfaces of said links and said stem being formed to permit universal movement of each link with respect to its adjoining links and of the inner end link with respect to the stem, and means for attaching the links one to the other and to the stem comprising a flexible cable threaded through said links and having its ends adjustably attached to said stem, said stem having a cavity in it, a pair of blocks slidably mounted in said cavity, means for attaching the ends of the cable individually to said blocks, and means for adjusting the blocks with respect one to another thereby to vary the effective length of said cable.
